Patented Nov. 10, 1914.

UNITED STATES PATENT OFFICE.

GUY W. CRAWFORD, OF FREMONT, MICHIGAN.

GAS-ENGINE VALVE.

1,116,999.

Specification of Letters Patent. Patented Nov. 10, 1914.

Application filed April 26, 1913. Serial No. 763,780.

To all whom it may concern:

Be it known that I, GUY W. CRAWFORD, a citizen of the United States, and a resident of Fremont, in the county of Nenwaygo and State of Michigan, have made certain new and useful Improvements in Gas-Engine Valves, of which the following is a specification.

My invention relates to valves particularly adapted for use in connection with gas engines, my object being to provide a rotary valve of novel construction whereby it will be self-balancing and self-grinding.

The means by which I accomplish the above object are shown in the accompanying drawing, in which—

Figure 1 is a vertical longitudinal section through a gas engine provided with my improved rotary valve. Fig. 2 is a vertical transverse sectional view therethrough. Fig. 3 is a view in diagram illustrating the relative position of the engine piston and my improved valve at the end of the suction stroke of the former. Fig. 4 is a similar view, the parts being in the position they will assume at the end of the compression stroke of the piston, and Fig. 5 is another similar view, the parts being in the position they will assume at the end of the explosion stroke of the piston.

Referring now to these figures, A designates the cylinder of a conventional upright gas engine, which is provided at its upper end with a rounded wall A', the sides of which are provided with circular openings and internal threads. This rounded wall A', as may be plainly seen, forms a substantially annular valve chamber a' in open communication with the upper end of the working chamber a of the engine, in which is located the usual piston B connected by a pitman b to the lower crank shaft C, this latter being provided exteriorly of the engine cylinder with a sprocket wheel c. The axis of the annular valve chamber a' extends at right angles to that of the engine cylinder a, and through the bearings of caps D and D', the latter of which is provided with an exhaust port d at one side of its center, and with an intake port d' above its center. These caps D—D' threadedly engage within the side openings of the valve casing formed by the rounded wall A', as before mentioned, and through their bearings extends the rotary valve stem

or shaft E' upon which is secured the valve E positioned between the caps. This valve E is circular in form and slightly less in diameter than that of its chamber a', and is centrally and annularly grooved in order to provide side flanges e and e', each of which is provided with a similar recess e².

The spindle or shaft E' is provided at an exterior point with a sprocket wheel e³, this sprocket wheel being, with a four cycle type of engine as I have shown, twice the size of the crank shaft sprocket wheel c and connected to the latter by a sprocket chain F.

In assembling the parts, caps D and D' are in the first instance adjusted so that their inner surfaces engage the outer side surfaces of the valve flanges e and e' snugly and evenly whereby to prevent leakage, the valve being thereafter perfectly balanced in operation by virtue of the pressure which is freely circulated entirely therearound from the working cylinder of the engine, and presses evenly against the inner surfaces of the flanges e and e'.

The spark plug G is threaded in the top of the valve casing, as shown in Figs. 1 and 2, and is controlled by make and break devices indicated at G', on the valve spindle or shaft E', and due to this fact I preferably form the intake port d' above the center of the valve chamber whereby the entering gas will circulate around the valve E and exercise a needful cooling effect upon the same. The valve E rotating in uniform relation with the piston B will uncover the ports d' upon the suction stroke of the piston, and rotating clockwise through the compression and explosion strokes of the piston will uncover the port d during the exhausting stroke, all of which may be plainly seen by a comparison of Figs. 3, 4 and 5.

I claim:

The combination with an engine cylinder provided at one end with a rounded wall open at its sides and forming a substantially annular valve chamber in open communication with the working chamber of the engine cylinder, of a valve mounted in the valve chamber and comprising a substantially circular member having a central annular groove forming similar side flanges around which pressure may freely circulate whereby to balance the valve sideways, each of which flanges is provided with

a recess or cut out portion whereby to insure endwise balance, a valve shaft extending through the valve chamber and on which the said valve is mounted, and caps closing the sides of the valve casing and engaging the sides of the valve, said caps being provided with substantially central

bearings whereby to support the valve shaft, and one of said caps being provided with intake and exhaust ports.

GUY W. CRAWFORD.
